PATTERN DRUM CONTROL MEANS

Ivan W. Grothey, Laconia, N. H., assignor to Scott & Williams, Incorporated, New York, N. Y., a corporation of Massachusetts

Application April 6, 1937, Serial No. 135,317

11 Claims. (Cl. 66—140)

This invention relates to circular knitting machines having means for forming embroidery patterns on the fabric by means of wrap or embroidery yarns during the knitting of the fabrics thereby and more particularly to means in a machine of the type described arranged for the knitting of stockings which provides for changes in the yarns of which the body of the stocking is knit so as to produce stockings having horizontal stripes as well as wrap embroidery patterns extending walewise of the stocking and it is an object of this invention to provide an improved means for controlling the introduction and withdrawal of the yarns of which the stocking is knit so as to provide improved patterning possibilities as to the horizontal stripes. It is also an object of this invention to provide a pattern drum for controlling the yarns, the cutter and clamp therefor and the means for insuring the engagement of all the yarns by the needles. It is a further object of this invention to provide means for controlling the starting and stopping of the pattern drum and for returning the pattern drum to the same position for its initial operation in the knitting of each stocking.

In the drawings in which a preferred embodiment of this invention is illustrated,—

Fig. 1 is a partial view in elevation of the head of a circular knitting machine of the Scott and Williams type equipped in accordance with this invention, parts being broken away to show other parts more clearly;

Fig. 2 is a plan view of the structure shown in Fig. 1 showing the body and wrap yarn finger, yarn pressers, cutter and clamp mechanism and part of their operating means;

Fig. 3 is a fragmentary view in elevation showing the means for pressing down the wrap yarns to prevent their being taken by the cutter and clamp mechanism;

Fig. 4 is a view in elevation of the pattern drum and related parts for controlling the insertion and withdrawal of the striping yarns, parts being broken away to show other parts more clearly;

Fig. 5 is a vertical sectional view of the structure of Fig. 4 taken as on line 5—5 of Fig. 4;

Fig. 6 is a fragmentary vertical sectional view taken as on line 6—6 of Fig. 5 and showing a detail of the means for lifting the wrap yarn presser at the time a yarn change is made by the pattern drum of Figs. 4 and 5;

Fig. 7 is a partial top plan view of the structure shown in Figs. 4 and 5;

Figs. 8 and 9 are partial vertical sectional views taken as on lines 8—8 and 9—9, respectively, of Fig. 7;

Fig. 10 is a view showing, developed in the plane of the drawings, a suitable arrangement of cams for the pattern drum of Figs. 4 and 5 for use in

knitting a stocking striped as shown in Fig. 22;

Fig. 11 is a partial vertical sectional view of the pattern drum of Fig. 4 showing the pawl for operating the drum and the operating means for the pawl, the pawl being shown in operative condition;

Fig. 12 is a fragmentary view similar to Fig. 11, the pawl being shown in inoperative condition;

Figs. 13, 14 and 15 are partial vertical sectional views of the pattern drum of Fig. 4 taken as on line 13—13 of Fig. 4 and showing the controlling means for the pawl of Figs. 11 and 12, Fig. 13 showing the positions of the parts of the controlling means while the pawl operates; Fig. 14 showing the positions of the parts immediately after the pawl has been rendered inoperative; and Fig. 15 showing the positions of the parts immediately before they are operated to release the pawl for operation of the drum;

Figs. 16 and 17 are views in elevation, detached from the remainder of the mechanism, of parts shown in Figs. 13 to 15;

Fig. 18 is a vertical sectional view of the pattern drum of Fig. 4 showing in elevation the means for rotating the pattern drum to a predetermined starting position prior to the beginning of the horizontal striping in the knitting of each stocking;

Fig. 19 is a sectional view of a friction or braking means for preventing movement of the pattern drum in excess of the movement of the operating means shown in Fig. 18;

Fig. 20 is a fragmentary view in elevation showing the means operated by the pattern chain for operating the pawl controlling means to release the pawl for operation of the pattern drum;

Fig. 21 is a fragmentary plan view of links of the pattern chain showing the relation thereto of the lugs for operating the means of Fig. 20; and

Fig. 22 is a diagrammatic view showing in elevation a stocking knit by a machine equipped in accordance with this invention.

In the drawings the invention is shown in connection with a circular knitting machine having a dial for the knitting of stockings having a ribbed top and plain fabric foot and leg and provided with wrap yarn guides for wrapping selected needles with embroidery yarns to form embroidery patterns therein as shown in the patent to Grothey No. 2,053,192, issued Sept. 1, 1936. In the drawings which show only so much of the machine as is necessary to illustrate the application of this invention thereto parts of the upper portion of the knitting machine are shown comprising the bedplate B, the needle cylinder 260, dial D, the wrap yarn fingers 761, the body yarn fingers F¹, F² and F³ operated by push rods 181 from the main pattern drum and arranged to feed the yarn to the needles at the throat plate 60

of the latch guard ring 550 which is pivotally mounted on the standard 551 in the usual manner. Associated with the needles and the yarn fingers is a cutter and clamp 176 operated from the main pattern drum (not shown) through a rod 177 connected to one arm of a bell crank lever 178 pivotally mounted on a pin 179 carried by the standard 551. The other arm of the lever 178 is connected by a link 175 to a bell crank lever 182 which operates the cutter and clamp and which is pivotally mounted on a bracket 174 carried by the latch ring 550. Also provided in a machine of this kind is a presser member 180 for insuring the taking of the body yarns by the needles which is pivotally supported on the pin 183 which supports the yarn fingers and is operated by a push rod 181 in the same manner as the yarn fingers F¹, F². There is also provided a presser member 186 positioned between the throat plate and the cutter and clamp mechanism for holding the wrap yarns down on the needles to position them below the body yarn and insure their plating on the outside of the fabric. The member 186 is withdrawn during each yarn change as in its operative position it would prevent the body yarns being lifted to the cutter and clamp mechanism. The member 186 is pivotally mounted on a bracket 187 secured to the latch guard ring and operated from the main drum by a push rod 181 which is connected to a crank 80 fixed on an end of a shaft 81 supported in the standard 551. The shaft 81 forms the pivot for the latch guard ring 550 and at its other end is provided with a crank arm 82 to which is attached a plunger 83 positioned to engage beneath an end of the presser lever 186.

To operate the yarn fingers to form horizontal stripes in a stocking as knit there is provided an auxiliary pattern drum 100 rotatably mounted on a shaft 109 supported by bracket members 105 carried by the machine frame. The drum 100 has cams 100^a, 100^b, 100^c and 100^d thereon arranged to cooperate with a plurality of fingers 101^a, 101^b, 101^c and 101^d having projections 102 arranged to engage cams on the pattern drum 100 so that the fingers are operated thereby. These fingers are pivotally mounted on a pin 103 supported in a bracket arm 104 which is mounted on the shaft 109 and is held in fixed position by a link 104^a which secures the upper end of the bracket arm 104 to the machine frame. The fingers 101^a, 101^b, 101^c engage beneath pins 181^a on the thrust rods 181 and are each held in engagement with the cams on the drum 100 by the weight of the parts and by the usual springs which draw down the yarn fingers so that when the cams are interrupted the fingers permit the thrust rods 181 to drop and the yarn fingers F¹, F², F³ to be lowered to introduce the yarns to the needles. When the fingers 101^a, 101^b and 101^c are raised by cams on the drum coming beneath the projections 102 on the fingers the thrust rods 181 are raised by the engagement of the fingers with the pins 181^a and raise the yarn fingers to withdraw the yarns from the needles.

To operate the drum 100 to rotate the cams beneath the fingers 101^a to 101^d, the drum is provided at one end thereof, the left end as shown in Figure 4, with a ratchet wheel 106, and a pawl 107, arranged to engage the wheel 106, is pivotally mounted on a lever 108 which pivots on the shaft 109. The lever 108 is operated by means of a rod 110 having mounted thereon a roller 110^a which contacts with a cam 111 fixed to rotate with a shaft 112. The rod

110 is slotted, as at 113, to hold the roller positioned with respect to the cam 111 while permitting movement of the rod 110 by the cam. A spring 114, secured to the pawl 107 and to the lever 108, biases the pawl to a position in which it engages with the teeth of the ratchet wheel 106 and a spring 115 secured to the rod 110 and to a suitable fixed portion of the frame holds the rod with the roller 110^a in engagement with the cam 111. The shaft 112 is driven from a gear 10 on the main drive shaft through gears 118, 117 and 116 in synchronism with the needle cylinder 260 so that the shaft 112 revolves once for each revolution of the needle cylinder causing the cam 111 and the rod 110 to be operated and to advance the pattern drum 100 one tooth of the ratchet wheel 106 for each revolution of the needle cylinder.

To control the operation of the pawl 107 there is provided a lever 125 pivotally mounted on the pin 103 and having a tapered projection or finger 126 arranged to be engaged by a pin 107^a fixed in one end of the pawl 107. The lever 125 is also provided with a pin 125^a at its lower end adapted to cooperate with a notch 127^a in a latching lever 127 which is pivotally mounted on a pin 128 secured in an extension of the bracket arm 104. The lever 127 is biased to an upper position by a spring 129 secured to the end of the lever and to a pin 130 supported by the lever 125. The pin 125^a, once engaged in the notch 127^a, is held thereby until the lever 127 is drawn down. To operate the lever 127 to release the pin 125^a there is provided a lever 131 pivotally mounted on the pin 128 and operated by means of a Bowden wire 133^a by lugs 133 on the pattern chain 134. The lever 131 is provided with an upwardly extending portion 131^a on which is pivotally mounted a lever 132 having an arm 132^a arranged to be engaged with the projecting portion 127^b of the lever 127 and an arm 132^b curved as shown in Figures 13, 14 and 15 and engaging an adjustable stop 133^c mounted on the lever 125. A spring 134 is connected between the lever arm 132^b and the pin 130 carried by the lever 125 and holds the lever 132^b engaged with the stop 133^c.

To operate the Bowden wire 133^a there is provided a lever 135 (Fig. 20) suitably mounted on the machine frame and carrying a block 135^a which engages with lugs 133 on the pattern chain 134. A spring 136 secured between the lever 135 and a portion of the machine frame biases the lever towards the pattern chain while a stop 135^b projecting from the lever 135 so as to engage with the machine frame limits the inward movement of the lever 135 and block 135^a towards the pattern chain. As shown in Figure 20 the lugs 133 engage under the block 135^a and force the lever 135 outwardly against the action of the spring 136. Operation of the lever 135 and Bowden wire 133^a by a lug 133 on the pattern chain 134 is arranged to draw the lever 131 downwardly against the action of a spring 138 secured between the free end of the lever 131 and an arm 139 fixed on the pin 103.

To prevent the pawl 107 operating the ratchet wheel 106 the drum 100 is provided with a pin or pins 140 placed in the drum in line with the finger 126 on the lever 125 so that as the pawl racks the ratchet wheel and drum and brings a pin 140 beneath the finger 126 the lever 125 and finger 126 are moved outwardly and position the pin 125^a in the notch 127^a of the lever 127, the lever 127 being held in engagement with the pin 125^a by the spring 129. When thus moved out-

wardly the finger 126 assumes a position which, because of the engagement of the finger 126 with the pin 107^a on the pawl 107, prevents the pawl from engaging when the rod 110 is drawn down 5 to engage the pawl with the following tooth on the ratchet wheel 106 to again rack the ratchet wheel 106 forward. This condition is shown in Figure 14, which shows the pawl 107 turned outwardly against the action of the spring 114 as the 10 pin 107^a travels along the finger 126. During the movement of the lever 125 and finger 126 to the 15 position of Fig. 14 by the pin 140 the pawl 107 is sufficiently far along in its operation that it is not disengaged from the tooth of the ratchet wheel 106 with which it is then in engagement and the operating stroke of the pawl during which the lever 125 is moved outwardly is not interrupted. By the completion of the operating stroke of the pawl the pin 140 is moved past the finger 126 to 20 a position, as shown in Figure 14, such that upon release of the pawl for further operation of the drum the pin 140 does not interfere with the return of the pawl to its operative position. The pins 140 may be placed so as to stop the drum 25 after a single operation of the pawl advances the ratchet wheel one step or after a desired number of operations up to a full revolution of the ratchet wheel.

To release the pawl 107 for further operation of the ratchet wheel 106 the lever 132, pivoted on the extension 131^a of the lever 131, must be brought to a position in which it will engage with the projection 127^b of the lever 127 and the lever 131 operated by the pattern chain to draw down 25 the lever 127 and release the lever 125. In order that the lever 132 may be thus operated there is a movement of the pattern chain to release the block 135^a from the lug 133 and permit the lever 131 to be raised by the spring 138. As the lever 131 is raised the lever arm 132^a bears against the back of the projection 127^b and rotates the arm 132^b of lever 132 away from the stop 133^c. The lever 131 is raised until the lever arm 132^a clears the projection 127^b and the spring 134 rotates the lever 132 to bring the arm 132^b thereof against the stop 133^c. This rotation of the lever 132 brings the lever arm 132^a thereof over the projection 127^b on the lever 127 as shown in Figure 15 so that upon downward movement of the lever 131 on engagement of the block 135^a by a lug 133 on the pattern chain 134 the lever 127 will be operated by the engagement of the lever arm 132^a with the projection 127^b lowering the lever 127 and permitting the spring 129 to rotate the lever 50 125 to release the pawl 107 for return to its operative position and to place the finger 126 on the lever 125 in position to be engaged by the next pin 140 on the pattern drum 100. The release of the block 135^a by a lug 133 on the pattern chain 60 need not be immediately followed by the operation of the lever 135 by a lug on the following pattern chain link as shown in Figure 21 as the lugs 133 need not be arranged on succeeding links but may be arranged in accordance with the pattern desired.

The cams on the drum 100 are arranged in accordance with the pattern desired and while the illustration shows three cam tracks, *a*, *b* and *c* for the control of yarn fingers F¹, F², F³, respectively, it will be understood that the invention is not limited to the number of cam tracks shown but a greater or less number of cam tracks and a greater or less number of yarn fingers may be used in accordance with the pattern desired. In 70 the construction shown the arrangement is such

that the projections 102 of the levers 101^a, 101^b and 101^c are raised from the pattern drum by cams 100^a, 100^b and 100^c of the cam tracks *a*, *b* and *c*, respectively, when it is desired to hold the corresponding yarn fingers out of action and are 5 in engagement with the surface of the pattern drum during the periods in which the yarn fingers are in action. Accordingly there are, as shown in Figure 10, cams which hold two of the yarn fingers out of action while the third yarn 10 finger is positioned for feeding yarn to the needles. Thus, in Figure 10 the yarn finger controlled by the cams 100^a of the cam track *a* is operative while the yarn fingers controlled by the cams 100^b and 100^c of the cam tracks *b* and *c*, respectively, are inoperative and the cams are so 15 positioned that the racking movement of the pattern drum 100 which renders the yarn finger controlled by the cams 100^a of the cam track *a* inoperative renders the yarn finger controlled by 20 the cams 100^b of cam track *b* operative.

In the machine illustrated, at each yarn change it is necessary that the cutter and clamp be operated; that the presser 186, which guides the wrap yarns, be withdrawn momentarily during the 25 period of yarn change; and that the presser 180 be lowered momentarily after the yarn finger presenting the new yarn has been lowered to insure the new yarn being taken by the desired needle. For these operations there are provided 30 on the pattern drum 100 additional cam tracks *d* and *e* having cams 100^d and 100^e, respectively. The cams 100^e are arranged to engage one arm of a bell crank lever 151 pivotally mounted on the pin 103 which has its other arm connected by a 35 rod 150 to that arm of bell crank lever 178 to which the rod 177 is connected thus establishing a connection to the cutter and clamp mechanism 176 through the bell crank lever 178, rod 175 and lever 176 for the operation of the cutter and clamp 40 mechanism by the cams 100^e at each yarn change controlled by the drum 100.

To operate the presser member 180 one of the cams 100^d on the cam track *d* passes from beneath the projection 102 of the finger 101^d each 45 time the drum 100 effects a yarn change, freeing the finger 100^d for movement towards the pattern drum 100 under the influence of a spring 101^f. The finger 100^d engages above a pin 181^a on the upper section of the associated telescoping thrust rod 181 (Fig. 8) and the downward movement of the finger 101^d draws down the upper portion of the telescoping thrust rod 181 against the action of a spring 181^b which holds the rod extended and permits the presser member 50 180 to be drawn down by a spring 180^a (Fig. 1) to push the newly presented yarn down to a position which insures the yarn being taken by the needles. The cams of cam track *d*, however, are arranged to again engage the extension 102 during the same racking movement of the drum 100 and raise the finger 101^d immediately after 60 the finger is lowered so that the upper section of the thrust rod 181 is again raised by the spring 181^b and the presser 180 maintained out of operation at all times except for the short time it engages the yarn to insure it being taken by the needles. Pivotally mounted on the pin 103 is a plate 152 supported from the finger 101^d by an adjustable support 153 so that the plate 152 is 65 lowered and raised with the arm 101^d at each operation of a yarn finger to effect a yarn change. Pivotally mounted on the plate 152 is a bell crank lever 154 having an arm 154^a thereof projecting alongside a push rod 181. This push rod 70 75

181 is provided with a lug 181^a against which the arm 154^a of the bell crank normally rests and beneath which the arm 154^a engages upon the lowering of the plate 152 by the movement of the arm 101^a, the bell crank lever 154 being operated by a spring 155 attached to the other arm 154^b of the bell crank lever and to the plate 152 to draw the arm 154^a beneath the lug 181^a. With the arm 154^a drawn beneath the lug 181^a 10 when the plate 152 is lowered, the push rod 181 is raised when the plate 152 is raised by the movement of the arm 101^a, thus operating the crank 80, shaft 81 and crank 82 to draw down the plunger 83 and permit spring 84 to withdraw the presser 186 for the period of the yarn change. The bell crank lever 154 is operated, almost immediately after raising the push rod 181, to release the push rod and permit the usual spring to operate the push rod to return the presser 186 20 to its operative position. For this operation of the bell crank lever 154 a bell crank lever 158 is pivotally mounted on the shaft 109 and has one arm 158^a thereof positioned to engage the arm 154^b of the bell crank lever 154 while the other arm 158^b is positioned to be operated by a cam 157 fixed on the shaft 112, the cam 157 being positioned with respect to the adjustable pin 158 in the arm 158^b so as to properly time the return of the presser 186 with respect to the operation of the yarn fingers. 25

In the selection of a pattern, such as shown in Figure 22, it is not always possible, or desirable, to have the pattern of such a design that the pattern drum 100 will always be in the position 30 for starting the striping of the next stocking when it makes its last operation in the knitting of a stocking. There is provided, therefore, a means for returning the drum 100 to a predetermined position after the completion of its 35 operation in the patterning of each stocking which means may operate either during the knitting of the toe or in the knitting of the rib top but preferably during the knitting of the rib top of each stocking, to rotate the drum 100 to a predetermined starting position. This means 40 comprises a pawl 160 which engages with the teeth of a ratchet wheel 161 at the opposite end of the drum 100 from the ratchet wheel 106. The pawl 160 is mounted to be operated by a cam 162 fixed on the shaft 112 so that at each rotation of the shaft 112 the ratchet wheel 161 is advanced one tooth. The ratchet wheel 161 is provided with a long tooth, as at 161^a, of such length that the movement of the pawl 160 by the cam 162 is insufficient to cause the pawl to move 45 off the tooth 161^a and upon return of the ratchet wheel to the position in which the pawl 160 rides on the tooth 161^a further movement of the ratchet wheel 161 and the pattern drum 100 50 ceases. To prevent operation of the drum 100 by the pawl 160 and ratchet wheel 161 at other times than when desired, a cam or guard plate 163 is mounted on the shaft 109 and is operated by a link 164 connected to an arm 164^a fixed to a 55 push rod 181 operated from the main pattern drum so that during the operation of the drum 100 to form the striped portion of the stocking and at all times except when the pawl 160 is to operate the drum 100 the cam 163 is positioned 60 to engage a pin 160^a on the pawl 160 and to prevent movement of the pawl 160 from operating the ratchet wheel 161. During the knitting of the rib top or other portion of the stocking when it is desired to return the drum 100 to its 65 starting position the cam 163 is shifted to the 70

75 starting position the cam 163 is shifted to the

dotted line position shown in Figure 18, releasing the pawl 160 to engage with the ratchet wheel 161 for operation of the drum to the predetermined starting position and before operation of the drum 100 by the pawl 107, the cam 163 is returned to the position in which it engages with the pin 160^a and prevents operation of the ratchet wheel 161 by the pawl 160. A plunger 190 mounted in an opening in a boss 104^a on the bracket arm 104 and forced into engagement with an end of the drum 100 by a spring 191 serves as a brake or drag on the movement of the drum by the pawls 107 and 160 and prevents movement of the drum in excess of movement of the pawls. 15

The stocking shown in Fig. 22 is knit, beginning at the rib top T and during the knitting of the top the pattern drum 100 is stepped around to its starting position. During this operation the thrust rods 181 controlling the yarn fingers 20 for the striping yarns are engaged by cams on the main pattern drum and the yarn fingers held out of action independently of the cams on the pattern drum 100. Where the pattern drum 100 is arranged to control the body yarn finger 25 so as to knit portions of the body yarn during the knitting of the stocking leg the cams on drum 100 will be arranged to permit the stepping of the drum to its starting position without interfering with the knitting of the rib top. Preferably the rib top is knit of a yarn supplied by a yarn finger not controlled by the pattern drum 100. 30

During the movement of the main pattern drum at the completion of the rib top T and the transfer of the dial loops to the cylinder needles for the knitting of the plain fabric of the leg L, the yarn of which the rib top is knit is withdrawn, the yarn of which the leg L is knit is inserted and all the thrust rods 181 are freed 40 by the main pattern drum for control by the pattern drum 100. At the desired time for making stripes a movement of the pattern chain 134 brings a lug 133 thereon into engagement with the lever 135, operating the lever 135, Bowden 45 wire 133^a and lever 131 to release the pawl for operation of the pattern drum 100. During the knitting of the leg L the pattern drum 100 is stopped and operated in accordance with the positioning of the pins 140 on the drum 100 and 50 their relation to the operation of the lever 135 by the lugs on the pattern chain 134 to produce the desired pattern. Such a pattern may be, as shown in Fig. 22, knit of contrasting yarns fed to the needles so as to form the narrow stripes s 55 and s', the wide stripes s² and the embroidery stripes or patterns s³. The pattern may be continued into the foot, the pattern drum 100 being held inactive during the knitting of the heel, and at the end of the pattern courses a pin 140 shifts 60 the pawl 107 and lever 125 outwardly for engagement by the lever 127 and all the lugs 133 on the pattern chain 134 having passed, the drum 100 is held inactive during the knitting of the toe and until pawl 160 is released to return the 65 drum 100 to its starting position. 70

What is claimed is:—

1. In a circular knitting machine, a pattern drum, a pawl for operating said drum, means for operating said pawl to advance said drum, a lever for engaging said pawl to prevent operation of said drum by said pawl, a latch for holding said lever with said pawl kept from operating said drum, pattern controlled means for operating said latch to release said lever to return 75

said pawl for drum operation and means on said drum for operating said lever to prevent said pawl operating said drum.

2. In a circular knitting machine, a pattern drum for controlling yarn fingers, a pawl for operating said drum, means for operating said pawl to advance said drum, means controlling the operation of said pawl, pattern controlled means for operating said pawl controlling means to release said pawl for drum operation, means on said drum operating said controlling means to operate said pawl to stop operation of said drum and resetting means for rotating said drum to a predetermined position while operation by said pawl is prevented.

3. In a circular knitting machine, a pattern drum for controlling yarn fingers, a pawl for operating said drum, means for operating said pawl to advance said drum, means controlling the operation of said pawl, pattern controlled means for operating said pawl controlling means to release said pawl for drum operation, means on said drum operating said controlling means to operate said pawl to stop operation of said drum, resetting means for rotating said drum to a predetermined position while operation by said pawl is prevented and means for rendering said resetting means inoperative during the operation of said drum by said pawl.

4. In a circular knitting machine, a pattern drum, a pawl for operating said drum, means for operating said pawl to advance said drum, a lever for engaging said pawl to prevent said pawl operating said drum, means on said drum for engaging said lever to shift said pawl, latching means for holding said lever with said pawl kept from operating said drum, a pattern means and means operated by said pattern means for operating said latching means to release said lever to return said pawl for drum operation.

5. In a circular knitting machine, a pattern drum, a pawl for operating said drum, means for operating said pawl to advance said drum, a lever for engaging said pawl to prevent said pawl operating said drum, means on said drum for operating said lever to engage said pawl, latching means for holding said lever with said pawl kept from operating said drum, a pattern means and means operated by said pattern means for operating said latching means to release said lever to return said pawl for drum operation, said means being attachable in different positions on said drum to vary the position in which said drum is stopped.

6. In a circular knitting machine, a pattern drum, yarn fingers controlled by said drum, a pawl for operating said drum, means for operating said pawl to advance said drum, a lever for engaging said pawl to prevent operation of said drum by said pawl, means on said drum for engaging said lever to shift said pawl, said means being attachable in different positions on said drum to vary the position in which said drum is stopped, latching means for holding said lever with said pawl kept from operating said drum, a pattern chain, means operated by said pattern chain for operating said latching means to release said lever to return said pawl to operate said drum and means for advancing said drum to a predetermined position with said pawl kept by said lever and latching means from operating said drum.

7. In a circular knitting machine, a pattern drum for controlling yarn fingers, a pawl for operating said drum, means for operating said pawl

to advance said drum, a lever for engaging said pawl to prevent operation of said drum by said pawl, means on said drum for operating said lever to engage said pawl, latching means for holding said lever with said pawl kept from operating said drum, a pattern chain, a release lever, means operated by said pattern chain for operating said release lever and means pivotally mounted on said release lever for engaging said latching means to operate said latching means to release said lever to return said pawl for drum operation upon operation of said release lever.

8. In a circular knitting machine, a pattern drum for controlling yarn fingers, a pawl for operating said drum, means for operating said pawl to advance said drum, a lever for engaging said pawl to prevent operation of said drum by said pawl, means on said drum for operating said lever to engage said pawl, latching means for holding said lever with said pawl kept from operating said drum, a pattern chain, a release lever, means operated by said pattern chain for operating said release lever and means pivotally mounted on said release lever for engaging said latching means to operate said latching means to release said lever to return said pawl for drum operation upon operation of said release lever, said pivotally mounted means being disengaged from said latching means upon operation of said release lever.

9. In a circular knitting machine, a pattern drum for controlling yarn fingers, a pawl for operating said drum, means for operating said pawl to advance said drum, a lever for engaging said pawl to prevent operation of said drum by said pawl, means on said drum for operating said lever to engage said pawl, latching means for holding said lever with said pawl kept from operating said drum, a pattern chain, a release lever, means operated by said pattern chain for operating said release lever and means pivotally mounted on said release lever for engaging said latching means to operate said latching means to release said lever to return said pawl for drum operation upon operation of said release lever and means on said pawl-engaging lever engaging said pivotally mounted means to disengage said pivotally mounted means from said latching means upon operation of said release lever.

10. In a circular knitting machine arranged to wrap embroidery yarns about the needles, a pattern drum, means for operating said drum, yarn fingers, means operated by said drum for operating said yarn fingers to effect striping by yarn changing, means positioning the wrap yarns on the needles for plating and means operated by said drum for withdrawing said yarn positioning means for a short period at each operation of said yarn fingers.

11. In a circular knitting machine arranged to wrap embroidery yarns about the needles, a pattern drum, means for operating said drum, yarn fingers for feeding the body yarns, means operated by said drum for operating said yarn fingers to effect striping by yarn changing, means positioning the wrap yarns on the needles for plating, means for engaging the body yarns with the needles and means operated by said drum for withdrawing said wrap yarn positioning means during each yarn change and for operating said body yarn engaging means to engage the body yarn with the needles at each yarn change.

IVAN W. GROTHEY.
